UNITED STATES PATENT OFFICE.

WILLIAM R. HENDRY, OF PAULLINA, IOWA.

THRESHING-MACHINE ATTACHMENT.

SPECIFICATION forming part of Letters Patent No. 678,564, dated July 16, 1901.

Application filed April 19, 1901. Serial No. 56,554. (No model.)

To all whom it may concern:

Be it known that I, WILLIAM R. HENDRY, a citizen of the United States, residing at Paulina, in the county of O'Brien and State of Iowa, have invented a certain new and useful Threshing-Machine Attachment, of which the following is a specification.

My invention relates to that class of threshing-machines in which an independent straw-stacker is used in connection with a separator; and the object of my invention is to provide improved means for connecting the separator with the stacker, whereby the stacker may be drawn from place to place by the separator, and improved means for transmitting power from the separator to the stacker, which is so constructed and arranged that the gearing may be left in operative condition at all times and shall accommodate itself when the machines are being moved from place to place to inequalities in the ground and when turning corners or when the machines are placed at an angle to each other.

In carrying out my invention I connect the stacker to the separator by means of a pole or tongue which has a pivotal connection with the separator, and I employ belt or chain gearing for transmitting power from the separator to the stacker. The belt or chain is arranged directly over the pole or tongue and passes over pulleys or sprocket-wheels, one of which is arranged directly over the king-bolt of the front axle of the stacker, while the other is arranged directly over the pivot at the front end of the tongue. A pulley or gear-wheel is arranged at the rear end of the separator on one side, and this is connected with a pulley or sprocket-wheel which is arranged over the front end of the tongue by means of a jointed shaft of an improved construction. The pulley or sprocket-wheel of the stacker, which is arranged directly over the king-bolt, is connected by means of a jointed shaft with a pulley which is arranged at the front end and on one side of the stacker, the organization being such that power may be transmitted from the separator to the stacker at any time, no matter what may be the relative position of the stacker to the separator, and the stacker may be drawn from place to place

over uneven ground or around corners without disturbing the gearing.

In the accompanying drawings, Figure 1 shows a side elevation of so much of a separator and stacker with my improvements applied as is necessary to illustrate my invention, and Fig. 2 shows a plan view thereof with parts broken away.

The separator A may be of any approved construction. I have only shown a portion of it, as my invention does not relate to any improvements in the construction of the separator proper. The same is true of the stacker B. The stacker is connected to the separator by a tongue C. This tongue is secured to a cross-beam D, which is connected by suitable devices d to the front axle E.

F indicates a fifth-wheel through which a king-bolt extends, and this fifth-wheel is connected with the body of the stacker in the usual manner or in any desired way.

The front end of the pole C is pivotally connected at c with a draw-bar G, which may be secured to the hind axle H of the separator, and it may be also secured and supported near its rear end by a hanger I, depending from the separator.

A pulley J is arranged at one side of the separator and near the rear end thereof. It may be belted or geared in any suitable way to the power-shaft or driving means. It is secured to a short shaft K, which has bearings in a bracket L, secured to the frame of the separator. To the shaft K is secured a shaft-section M, which has a universal joint or coupling N, with another short shaft-section O. The shaft-section O is made square and enters a sleeve P, having a square bore, in which the shaft-section O is free to move lengthwise. The sleeve P is connected by a universal coupling Q with a short shaft R, having bearings in a bracket S, secured to the front end of the tongue or pole C. A pulley or sprocket-wheel T is secured to the shaft R between the bifurcated side pieces s of the bracket S. This pulley is connected by means of a chain or belt U with a sprocket-wheel V on a short shaft v, mounted in bearings in the upper end of the bracket W, which is mounted on or secured to the rear end of

the tongue or pole C. The shaft *v* is connected by means of a universal joint or coupling X with the arm *y* of a sleeve Y, which has a square bore, into which extends a square shaft Z, connected by a universal joint or coupling *a* with the arm *b*, projecting from a short shaft *e*, having bearings in a bracket *f*, secured to the frame of the stacker B. A pulley *g* is secured to the end of the shaft *e*.

10 By this organization the separator may be drawn from place to place and drag the stacker after it, and power may be transmitted from the separator to the stacker no matter what may be the relative position of the stacker to the separator. It is not necessary to uncouple any parts of the gearing when moving the machines, as the gearing accommodates itself to any changes in relation between the two machines.

15 20 It will be observed that the pulley or sprocket-wheel V is arranged directly over the king-bolt of the stacker, while the pulley or sprocket-wheel T is arranged directly over the pivot *c*, connecting the front end of the pole with the separator. The gearing is adapted to flex or bend vertically, if necessary, when traversing uneven ground, and it is adapted to flex or bend horizontally in the manner indicated in Fig. 2 when the machines are rounding a corner or when the position of one machine is changed relatively to the other.

25 30 35 By the organization shown I am enabled to use sprocket-gearing, which has many advantages, and the machines may be placed with

such relation to each other as to best accommodate them to the situation where they may be placed when at work.

I claim as my invention—

1. The combination of the separator, the stacker, a pole or tongue connecting the separator and the stacker, a driving-pulley at the side of the separator, a pulley arranged over the front end of the tongue, a jointed shaft connecting the driving-pulley with the pulley arranged over the front end of the tongue, another pulley arranged over the king-bolt of the stacker, a belt connecting the last-mentioned pulley with the pulley over the front end of the tongue, a pulley at the side of the stacker, and a jointed shaft connecting the pulley arranged over the king-bolt with the pulley at the side of the stacker.

2. The combination of the separator, the stacker, a pole connecting them, a pulley arranged over each end of the pole, a belt connecting these pulleys, pulleys at the side of the stacker and separator, and shafts connecting the pulleys at the sides of the separator and stacker with the pulleys arranged over the tongue, said shafts having sliding portions and universal couplings, substantially as described.

In testimony whereof I have hereunto subscribed my name.

WILLIAM R. HENDRY.
